HOT LINE STICK

John B. Mays, Crossville, Tenn.

Application April 10, 1941, Serial No. 387,949

2 Claims. (Cl. 81—53)

This invention relates to what are generally known in the art as "hot line sticks," and particularly to a type of such stick as is equipped for holding, applying, tightening and releasing a screw-clamp used for connecting a lead or tap to a live conductor or transmission line.

An object of the present invention is to improve generally upon such types of sticks, and particularly to provide such a stick as and for the purpose stated as will permit the operator to remain in a safe position on the pole while manipulating the stick.

A further object of the invention is to provide a "stick" of this character that will be free of all seams or grooves thereby making the same safe for use in damp or wet weather and consequently increase the safety factor involved.

A further object of the invention is to provide a device of this character which, in addition to being used for the purpose above stated, may be also used with equal facility and to advantage in the removing and replacing of fuse barrels or holders.

The invention together with its objects and advantages will be best understood from a study of the following description taken in connection with the accompanying drawing wherein—

Figure 1 is an elevational view of a "hot line" stick embodying the features of the present invention and illustrating the manner of using the same.

Figure 2 is an elevational view of the stick taken at right angles to Figure 1, and

Figure 3 is an enlarged longitudinal sectional view through the head of the stick illustrating certain details hereinafter more fully referred to.

Referring more in detail to the drawing, it will be seen that in the preferred embodiment thereof the stick comprises an elongated handle 5 which may be made of wood or other dielectric or non-conductive material, and a head 6 mounted on one end of the stick.

The head 6, forming the salient feature of the invention, embodies a tubular body 7 that has one end thereof sleeved on one end of the handle 5 and shrunk or otherwise made fast thereto.

Sleeved on one end of the tubular body 7 and secured thereon against longitudinal and rotative movement relative to the body 7 through the medium of oppositely disposed pins 8 is a relatively short cylinder or socket 9.

The cylinder or socket 9 is provided in diametrically opposite sides thereof with slots 10 elongated longitudinally of the cylinder or socket 5

9 and opening at one end through the top edge of the cylinder or socket 9 as shown.

The socket or cylinder 9 accommodates a substantially U-shaped hook 11, the arms of which extend through one of the slots 10 and the bight, or curved end of which is accommodated in the other of the slots 10 as clearly shown.

The hook 11 has one leg 11a thereof suitably secured to the head end of an elongated bolt 12 that extends down into the cylinder 7 through an axial opening in a plug 13 that is confined in the upper end of the body 7.

The body 7 is provided on its periphery with a groove 14 that accommodates the inner pointed ends of the pins 8 as shown in Figure 3.

The hook 11 is yieldably urged inwardly of the socket or cylinder 9 through the medium of a coil spring 15.

The spring 15 is disposed about the bolt 12 and has one end impinging against the plug 13 and an opposite end impinging against a washer 16 that is confined on the bolt 12 between said one end of the spring 15 and a nut 17 threaded on the free end of the bolt as shown.

Preferably the washer 16 is of a diameter as to have a more or less snug working fit within the cylinder 7.

The longer and somewhat angularly shaped leg 11b of the hook 11 is provided at its free extremity with a knob or enlargement 18 as shown.

As previously stated the implement herein illustrated and described is designed primarily for application to and the operation of the eye screw 19 of a clamp of the type used for connecting a lead or tap to a live conductor or transmission line; and which clamps vary considerably in number and design, but are all, generally speaking, characterized by a clamping screw such as referred to above as screw 19.

In using the device to rotate the screw 19 for effecting either a clamping engagement of the clamp with the work, or the release of the clamp, the parts of the implement are normally in the full line position shown in the drawing. In this

position, the headed end 18 of the leg 11b of hook 11 is first passed through the eye of the screw 19. When this has been accomplished the operator pulls downwardly on the handle 5, and the screw 19 being substantially stationary with respect to the stick, the socket or cylinder 9 moves downwardly so that the upper edge thereof, against the action of spring 12, clears, or substantially clears the leg 11a of the hook 11. This will permit the leg 11b to be passed further through the eye of the screw 19 so that when this downward

pull on the handle 5 is released, the parts will then return to the position shown in the drawing, and in which position the eye of the screw 19 is engaged with the leg 11b within the confines of the socket or sleeve 9 and is thereby retained in engagement with the hook 11 against casual displacement as the tool is being manipulated to turn the screw 9 for threading the same home or loosening the screw as found desirable.

Obviously, in connection with the above, the hook 11 being seated in the socket 9 and engaged with the screw eye as shown in Figure 3, all the parts of the head 6 will turn with the handle 5 as a unit, thus causing the screw 9 to turn for advancing or retracting the screw.

When the screw 9 has been threaded to the desired position of adjustment, a downward pull is again exerted on the handle 5 until the upper end of the socket or sleeve 9 completely clears the leg 11a of the hook 11. When this clearance has been obtained, the handle 5 is given a turn in the desired direction so as to bring the slots 10 in the sleeve 9 to a position substantially at right angles to the position the slots are shown in in Figure 3 so that only solid end edge portions of the sleeve 9 are then presented to the leg 11, so that the leg 11 will then rest on the upper end edge of the sleeve 9. When this has been accomplished the leg 11b of the hook may be readily withdrawn through the eye of the screw 19 and the stick thereby wholly disengaged from the screw 19. In this connection it will be appreciated that by reason of the pin and groove connection between the tubular member 1 and the plug 13, the sleeve 7 and associated parts may be readily rotated about the bolt 12 as an axis and relative to the hook 11 when it is desired, as above stated, to place the slots 10 of the cylinder or socket 9 at substantially right angles to the longitudinal dimensions of the hook 11.

As will also be clear to those skilled in the art, this device may be used with equal facility in replacing and removing fuse barrels or holders.

It is thought that the advantages of a "hot line stick" embodying the features of the present invention will be clear to those skilled in the art without further detailed description.

Also, while I have herein illustrated and described the preferred embodiment of the invention, it is fully appreciated that changes may be made therein by those skilled in the art, and therefore I do not wish to unnecessarily limit myself to the precise embodiment illustrated.

Having thus described the invention what is claimed as new is:

1. A manipulating stick for hot line, eye screw-operated clamps, comprising a handle, a head on one end of said handle, said head embodying an axially positioned tubular socket open at its upper end and provided at diametrically opposite sides with longitudinal slots, a hook normally accommodated within said socket and having portions thereof normally engaging in said slots to retain said hook against rotative movement relative to said socket, a spring mechanism confined within said head and engaged with said hook and normally urging the hook inwardly of said socket; and said hook having a free terminal normally projecting outwardly of said socket through one of said slots to facilitate initial engagement of the hook with the eye screw of the clamp, said hook being slidable in said slots to withdraw the same out of said pocket in opposition to said spring means and rotatable when withdrawn relative to said slots to seat the same on the outer end of the socket.

2. A manipulating stick for hot line eye screw-operated clamps, comprising a handle provided on one end thereof with a head, said head embodying a cylindrical socket having opposed slots in the peripheral wall thereof opening through the upper edge of the wall, a bolt slidably and rotatably mounted within said head, a hook secured to one end of the bolt and normally disposed inwardly of said socket, a spring device connected with the bolt normally urging the same in one direction for yieldably retaining said hook inwardly of said socket; said hook being substantially U-shaped in side elevation and having the legs thereof at the open end of the U normally accommodated in one of said slots, with the closed end of the U normally accommodated in the other of said slots, and one of said legs being adapted to be inserted into the eye of the clamp-operating screw for turning said screw; the whole assembly being such that upon a downward pull on the handle of said stick with the hook engaged as aforesaid with the clamp-operating eye screw said socket is movable downwardly relative to the hook to clear the latter, with said handle and head assembly rotatable as a unit about the bolt so as to bring portions of the wall of the socket between the slots thereof into engagement with the hook to retain the hook substantially wholly exteriorly of the socket.

JOHN B. MAYS.
